J. RIFKIN

DISPLAY BOX

Filed Jan. 13. 1923

FIG. 1.

FIG. 2.

Inventor

JOSEPH RIFKIN

By his Attorney Edwin Leisohler

UNITED STATES PATENT OFFICE.

JOSEPH RIFKIN, OF NEW YORK, N. Y., ASSIGNOR TO L. HELLER & SON, INC., OF NEW YORK, N. Y., A CORPORATION OF NEW YORK.

DISPLAY BOX.

Application filed January 13, 1923. Serial No. 612,562.

To all whom it may concern:

Be it known that I, JOSEPH RIFKIN, a citizen of the United States of America, residing at 3647 Broadway, New York city, 5 New York, have invented a new and useful Improvement in Display Boxes, of which the following is a specification.

This invention relates to jewel display boxes and has for its object to provide a 10 body and cover connected to the ends of connecting links or stays, so that the cover may be moved relatively of the body to a substantial upright position, while the body is suspended at one end by the links to assume a slight forward inclined position.

The invention is illustratively exemplified in the accompanying drawing, in which, Figure 1 is a perspective view of my improved case in display position, and Figure 20 2 a is a perspective view of the same in closed position.

Referring to the drawing, 10 designates the body of the box and 11 the cover therefor. Both body and cover may be substantially 25 the same construction, as shown, with suitable lining material 12 disposed on the inside. The body 10 and cover 11 comprise sides 13 and ends 14, said sides being upright walls carried by the bottom and top 30 portions.

The body 10 and cover 11 are linked together by means of stays or links 15 comprising straight steel pieces pivoted at their ends to the ends 14 of the two portions of 35 the box. The ends of both links pivoted to the ends 14 of the body are pivoted about suitable studs 16 disposed axially of each other at points on the ends 13 closely adjacent the rear wall or side 13, while the 40 other ends of the links are pivoted directly

on the longitudinal axis of the cover 11 by means of suitable pivot members 17 disposed axially of each other on the ends 14.

To manipulate the box to place it in display position it is necessary to simply 45 hold to body 10 while the cover 11 is swung with the links 15, which move about their pivots 16 and 17, until the cover has assumed an upright position which is slightly inclined towards the rear thereof, and the 50 rear end of the body has been raised by the links. The links are substantially shorter than the distance measured by one half the length of the ends 14, in which case the rear side of the body 10 will abut the inside of 55 the cover 11 to form a fulcrum below the center of the pivots 17. This construction provides a three point or triangular lock to hold the body suspended at an incline and the cover erect, as shown.

What I claim is:

A display box, comprising similar body and cover sections, and links pivoted at opposite ends to the body and cover, the pivot on the body being disposed in the ends thereof adjacent the rear side and the pivot on the cover being disposed in the ends and midway of their length, and in which the said links are of a length substantially less than the distance measured by one-half the 65 length of the said ends, whereby, when the cover is in upright position the rear side of the body will be suspended against the inside of the cover and the body will assume an inclined position with respect to 70 the cover, substantially as described.

In testimony whereof, I, JOSEPH RIFKIN, have signed my name to this specification this 5th day of January, 1923.

JOSEPH RIFKIN.
